(57) **CLAIM**

The ornamental design for a jaw portion of calipers, as shown and described.

DESCRIPTION

FIG. 1 is a front view of the invention;

FIG. 2 is a back view of the invention;

FIG. 3 is a right side view of the invention;

FIG. 4 is a left side view of the invention;

FIG. 5 is a top view of the invention;

FIG. 6 is a bottom view of the invention; and,

FIG. 7 is a perspective view of the invention.

Portions of the figures represented with broken lines are not part of the claimed design.
